[57] CLAIM

The ornamental design for an ice cream cone drip cup, as shown and described.

DESCRIPTION

FIG. 1 is a front elevational view of the ice cream cone drip cup showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The ice cream in FIG. 4 is shown in broken lines for illustrative purposes only.
